UNITED STATES PATENT OFFICE.

FERNANDIEZE M. SIMMONDS, OF CHICAGO, ILLINOIS.

CARD.

1,208,391.

Specification of Letters Patent. Patented Dec. 12, 1916.

Application filed March 23, 1916. Serial No. 86,152.

To all whom it may concern:

Be it known that I, FERNANDIEZE M. SIMMONDS, a citizen of the United States of America, and resident of Chicago, Cook county, Illinois, have invented a certain new and useful Improvement in Cards, of which the following is a specification.

My invention relates to cards for mailing purposes, such as post-cards, etc., and cards for various other purposes, and other similar articles.

The object of my invention is to provide a post-card or other card which can be transmitted through the mails, like an ordinary post-card, or which can be delivered in other ways, depending on the particular use to be made thereof, in a perfectly flat condition, and which can then be folded to form an easel-like article for the desk, or for use in other places, such as a picture or calendar, thereby providing a novelty which will readily attract attention and which can be used to advantage for advertising purposes, as well as in various other ways.

To these and other useful ends, my invention consists in matters hereinafter set forth and claimed.

In the accompanying drawings:—Figure 1 is a face view of a post-card embodying the principles of my invention, showing the same in flat condition for mailing. Figs. 2, 3 and 4 are perspective views illustrating the method of folding the said post-card into condition for use on the desk as a picture or calendar, the folding operation resulting in an easel-like article. Fig. 5 is a vertical section on line 5—5 in Fig. 4.

As thus illustrated, my invention comprises a rectangular card having a front section A and a back section B, the two sections being flexibly connected together along the transverse lines *a*, and the front section A having a top portion C which is practically entirely separated from the section B along its top and side edges, being held in place merely by the small breakable portion C which is perforated to make it cut or tear easily. The section B has a wide shallow notch *b*, and is also provided across the corner portions thereof with oblique fold lines *D*, so that the triangular corner portions *d* can be folded relative to the body portion of this section. The section A is provided near its lower end with a tongue *E* which can be bent backward to form a catch. When it is desired to fold the card, the portion *c* is

broken either by cutting or tearing the same, and the section B is then folded backward along the line *a* in the manner shown in Fig. 2. The corner portions *d* are then folded in the manner shown in Fig. 3, and the section B is flexed slightly to bring the edge of the notch *b* back of the tongue *E*—that is to say, between this tongue and the rear surface of the section A, in the manner shown in Fig. 5. The card is thus reduced to an easel-like article which can be used in the manner shown in Fig. 4. In this condition, the lower edge of the section A rests upon the desk or table, and the triangular corner portions *d* extend backward therefrom to provide the easel construction and hold the folded card in upright position. Thus, a post-card is provided which can be sent through the mail in a perfectly flat condition, as shown in Fig. 1, and which can then be folded to form an easel-like picture or calendar, as shown in Fig. 4. The space below the picture may have a calendar or other printed matter thereon, and can be used for advertising purposes.

It will be understood, of course, that I do not limit myself to any particular use or purpose, as a card of the kind shown and described may be used for various purposes. For example, it may be used like an ordinary post-card, or as a souvenir post-card, etc. Again, it can be used as a valentine card. In addition, it can be used as a price card—that is to say, it can be placed by the merchant in a window to feature various articles, with advertising matter and prices. Also, as will be readily understood, it may be used as a guest card, or as a place card at the dinner table. In stores, it can be used on the counter as a display card, and may have small articles attached thereto, such as bottles of perfume, nail files, and similar small articles. Obviously, a card of this kind can be employed as a calendar, and for various other purposes.

It will be understood that Fig. 1 shows the obverse side of the card, and that the other or reverse side will bear the address and stamp, etc., when the card is used as a post-card or for mailing purposes. I may also place on the said reverse side instructions for the operation and use of the card, such, for example, as the Figs. 2, 3 and 4 of the accompanying drawings, so that the person receiving the card will see at a glance how to fold the same. The seal *F* may be

merely a red spot of ink on the surface of the card, or it may be actually a thin paper seal of any suitable or desired color. In any event, this seal will have a portion *c* located 5 centrally thereof, so that when this portion is broken, one-half the seal will remain on the portion *C* of the card, and the other half on the section *B* of the card. The words "Break seal," or some similar expression, can 10 be printed on the said seal, or directly above the same, as shown in Fig. 1, if such is desired. It will also be understood, of course, that the lines *a* and *D* are score lines, formed by cutting partially through the sheet material, but that the lines *G* and *g* are formed 15 by cutting entirely through the sheet material.

I do not limit myself to the exact form and construction shown and described.

20 What I claim as my invention is:—

1. An article of the character described, comprising a single thickness of material of suitable shape to form a card, having a front section to stand upright on its lower edge 25 and a back section which is foldable flatwise against the back of the front section and provided with means flexible into position to support the two sections upright in parallel relation to each other, thereby to form 30 an easel-like article for the desired purpose, said front and back sections being partially detached from each other and ready to fold except for a small breakable portion which keeps the entire card flat to prevent accidental folding thereof, and means to retain the folded back section flatwise against the rear surface of the front section.

2. An article of the character described, comprising a single thickness of material of 40 suitable shape to form a card, having a front section to stand upright on its lower edge and a back section which is foldable flatwise against the back of the front section and provided with means flexible into position 45 to support the two sections upright in parallel relation to each other, thereby to form an easel-like article for the desired purpose, said front and back sections being partially detached from each other and ready to fold 50 except for a small breakable portion which keeps the entire card flat to prevent accidental folding thereof, and said front section having a top portion formed by said partial detachment and held in place at the upper 55 end thereof by said breakable portion, and means to retain the folded back section flatwise against the rear surface of the front section.

3. An article of the character described, 60 comprising a single thickness of material of suitable shape to form a card, having a front

section to stand upright on its lower edge and a back section which is foldable flatwise against the back of the front section and provided with means flexible into position 65 to support the two sections upright in parallel relation to each other, thereby to form an easel-like article for the desired purpose, said means consisting of foldable corners on the back section to extend rearward when 70 the two sections are flatwise together and thereby form the easel-like support for said article.

4. An article of the character described, comprising a single thickness of material of 75 suitable shape to form a card, having a front section to stand upright on its lower edge and a back section which is foldable flatwise against the back of the front section and provided with means flexible into position 80 to support the front section, thereby to form an easel-like article for the desired purpose, said front section having a tongue at the lower edge thereof, and said back section being notched for insertion between said 85 tongue and the front section, thereby to hold the sections flatwise together.

5. An article of the character described, comprising a single thickness of material of suitable shape to form a card, having a front 90 section to stand upright on its lower edge and a back section which is foldable flatwise against the back of the front section and provided with means flexible into position to support the two sections upright in parallel 95 relation to each other, thereby to form an easel-like article for the desired purpose, said means including a portion which extends backward to form a prop for the article when the two sections are flatwise together.

6. An article of the character described, comprising a single thickness of material of suitable shape to form a card, having a front section to stand upright on its lower edge 105 and a back section which is foldable flatwise against the back of the front section and provided with means flexible into position to support the two sections upright in parallel relation to each other, thereby to form an 110 easel-like article for the desired purpose, said means including a portion which extends backward to form a prop for the article when the two sections are flatwise together, said front section having a portion 115 to stand up above the fold line between the two sections, and said back section having an opening which is occupied by said last mentioned portion before the card is folded.

Signed by me at Chicago, Illinois, this 4th 120 day of March, 1916.

FERNANDIEZE M. SIMMONDS.
